FOLDING OVERHEAD DOOR

Matt Mattson, Hibbing, Minn.

Application February 6, 1948, Serial No. 6,759

2 Claims. (Cl. 160—189)

1

This invention relates to doors, particularly garage doors, and has special reference to such doors which are folded overhead when open.

One of the principal objects of the instant invention is to provide a foldable overhead garage door which is simple to install and operate and which is relatively inexpensive.

Another object is to so arrange the operating mechanism of the door that very little effort is required to either open or close same.

Another object is to provide an efficient locking arrangement for the door.

Other objects and advantages will appear as the description of the invention proceeds.

In the accompanying drawing forming a part of this application:

Fig. 1 is a perspective view of an overhead door constructed in accordance with the invention showing the inner side thereof.

Fig. 2 is a broken fragmental plan view of the door locking mechanism and a portion of the operating mechanism.

Fig. 3 is a sectional view on the line 3—3 Fig. 2.

Fig. 4 is a perspective view of the combined latch and lock lever.

Fig. 5 is a fragmental perspective view of the spring controlled end of the door's operating mechanism.

Fig. 6 is a perspective view showing the attachment of the lifting arm or lever to the upper section of the door.

Fig. 7 is a sectional view of a portion of the mechanism shown in Fig. 6 to illustrate the roller on which the lifting lever is carried.

In the drawing, the reference numerals 1—1 indicate the side frame members of a common garage door opening.

The instant door which is installed to close the above mentioned opening is made in two substantially equal parts, the upper section 2 and the lower section 3, the same being hingedly united along their abutting edges, the point of bend or pivot being on the outer side of the door, the door being adapted to be folded upwardly on the inside of the garage or building. The upper section 2 of the door is hingedly installed on the upper transverse member of the door frame (not shown) as by the hinges 4—4 to complete the hinged installation of the door over the opening.

To facilitate the opening and closing of the door and to insure its remaining in open or closed position as desired I have installed a weight 5 and a contractile spring 6, the weight 5 is instrumental in providing ease of upward motion for the lower section 3 of the door and the spring 6 is instrumental in aiding the upward movement of the upper section of the door, however, it is deemed that in the cooperative use of the two, each will aid in the movement of both sections.

The lifting mechanism which is weight oper-

ated comprises a shaft 7 which is rotatably mounted at each end thereof in a bearing 8, the latter being supported on a suitable bracket 10 to properly position the shaft 7 to permit of the rotation of the three pulleys or drums 11, 12, and 13 which are fixed on the shaft to rotate therewith, one of the pulleys being on one end of the shaft and two of same on the other end thereof, one on either side of the bearing 8. The outer drum 11 is the winding drum or driving drum for the shaft 7, the same having wound thereon a length of rope or cable 14 at the end of which the weight 5 is carried to cause the shaft 7 to be rotated by the pull of the weight 5 around the drum 11.

A length of cable 15 is wound on each of the pulleys 12 and 13, but in a reverse direction to the winding on the drum 11, thus, when the drum 11 is being rotated by the downward pull of the weight 5, the winding of the drums 12 and 13 will be such as to tend to wind more cable or rope thereon. The end of the cables 15 of each drum 12 and 13 is attached to the extreme lower corners of the bottom section of the door by means of a rotatable or oscillatory lug 16, as shown in Figs. 2 and 3, thereby, upward stress is applied to the door by the weight 5 in the manner above pointed out. Of course, it is deemed apparent that the size of the weight 5 may be adjusted to give the desired amount of lift or upward stress to the door.

To facilitate the upward folding of the door sections and to guide same as they travel upwardly, a track 17, preferably a strip of metal, is fixed along the entire edge of the side frames 1—1 adjacent the door opening, and a guide 18, also of metal, is installed parallel to and spaced a suitable distance from the track 17, see Fig. 2.

A roller 19 is rotatably carried adjacent the lower corners of the lower section 3 of the door and is adapted to travel or ride intermediate of the track 17 and the guide 18 so that the lower edge of the door is maintained or held in position to travel upwardly in a vertical plane only, while the door sections are hinged inwardly and upwardly at the center of the door, see the dotted lines, Fig. 1.

To further facilitate the operation of the doors, means is provided to apply inward and upward stress on the lower end of the upper section of the door. The said means comprises a shaft 20 which runs parallel to the shaft 7 and is journaled at each end in a suitable bearing which is supported on the bracket 10 extending from the respective side frames 1—1 see Fig. 5.

One end of the shaft 20 extends through the bearing and has a crank arm 21 extending at substantially a right angle thereto, which is normally held in substantially vertical position when the door is closed. To the outer end of the arm 21 a U-shaped link member 22 is pivotally secured,

and a contractile spring 6 is carried intermediate of the link 22 and a bracket 24 which is fixed to the adjacent side frame 1 a suitable distance from the link 22 to provide proper tension on the crank arm by the spring.

A relatively stiff lever 25 is fixed at each end of the shaft 20 inwardly of its bearings, the levers extending downwardly and being opposed to but not necessarily aligned with the crank arm 21. These levers are, preferably, of a length to reach a point on the upper door section at least beyond the center thereof where an elongated bracket-like slide or guide 26 is installed on the upper section of the door substantially as shown in the drawings, Fig. 1. The main body portion of the 15 guide 26 is spaced from the door somewhat so that a roller 27 may be operated on the inner side of same, said roller being carried at the outer end of the lever 25 as by the bracket 28 fixed thereto.

With the lever 25 thus mounted, the stress of 20 the spring 6 tends to raise the lower end of the upper section 2 of the door as is readily seen from the drawings. When the door is moved upwardly, the lower end of the lever 25 pulls upwardly on the brackets 26 which are fixed to the door section 2 by means of the roller 27 on the inner side thereof, and as the door moves upwardly the arm is moved downwardly on the bracket 26 as shown in dotted lines Fig. 6, the roller permitting free movement thereof, due to the different pivot points of the lever and the door section.

It is deemed apparent from the above that by 25 properly adjusting the tension of the spring 6 and the size of the weight 5, very little effort will be required to either raise or lower the door.

When the door is in raised or uppermost folded position, the same may be pulled down by means of a suitable foldable handle or rope 29 secured to the bottom of the door.

In raising the door from the inside and inward pull on the handle 30 is usually sufficient to send the door into folded uppermost position. When opening the door from the outside it is only necessary to push inwardly on the door adjacent the hinged connection of the two sections.

A novel means for locking the door in closed position is illustrated in Figs. 2, 3 and 4 of the drawing wherein 31 indicates the latch lever which is operated by means of either the inner knob or handle 32 or the outer handle 33, the latter being united by a square shaft which extends through the square opening 34 in the lever 31.

When in locked or closed position the extension or latch portion 35 on one end of the lever 31 engages the inner side of the track guide 18 and thereby prevents the door folding inwardly, there being another extension 36 at the opposite end of the lever 31 which has an operating rod 37 pivotally attached thereto which is reciprocated by the turning of the lever 31 and which may be either engaged beneath the guide 18 on the opposite side of the door or disengaged therefrom by turning of either of the handles 32 and 33, thereby, the door may be held in closed position as desired.

The locking means for the door comprises any suitable locking device 38 which has provisions for being unlocked and the bolt 39 withdrawn by a key 40 on the outside and a knob 41 on the inside for withdrawing the bolt. In the instant case, the

latch lever 31 has a notch 42 on its upper edge into which the bolt 39 extends when the lever 31 is in position to hold the door closed, the bolt being spring biased to outward position, whereby the latch lever 31 may not be operated when the bolt is in extended position.

When the lever 31 is turned so as to permit the door to be folded upwardly (after the bolt has been withdrawn), the bolt 39 is held inwardly as 10 by the angular projection 43 on the lever 31 and the bolt automatically locks the lever 31 in closed position as soon as it is turned to that position, as is apparent from the drawings.

Having thus described my invention, what I claim is:

1. A door within a frame, said door being adapted to be folded upwardly when open comprising an upper and a lower door section, said sections being hingedly united along adjacent horizontal edges, said upper section being hingedly connected to the upper transverse member of said frame, and means for expediting the opening and closing of said door comprising a pair of shafts journaled adjacent the top of said frame, one of said shafts having a lever secured to the upper section of said door and spring means for applying upward stress to said lever and said door section, and the other of said shafts having a plurality of drums fixed thereto, one of said drums having a weighted cable wrapped thereon to tend to rotate said shaft, and another of said drums having a cable wound thereon in a direction opposite to that of said first mentioned cable, said last mentioned cable being secured to the lower edge of said bottom door section to apply upward stress thereto.

2. A door within a door frame, said door being adapted to be folded upwardly when open comprising an upper and a lower door section, said sections being hingedly united along adjacent horizontal edges, said upper section being hingedly connected to the upper transverse member of said door frame, and means for expediting the opening and closing of said door comprising 40 a pair of shafts journaled adjacent the top of said frame, one of said shafts having a lever secured thereto and to a portion of said upper door section, a crank arm on said shaft, and a spring fixed at one end to said crank arm and at the other end to said frame for applying upward stress to said upper door section by means of said lever, and the other of said shafts having a plurality of drums fixed thereto, a cable wound on one of said drums and having a weight fixed thereto, 45 and a second cable wound on another of said drums in a direction opposite to said first cable, the free end of said second cable being secured to the bottom of said lower door section.

MATT MATTSON.
